T. PETERS.

AIR PUMP FOR WATER DISTRIBUTING SYSTEMS.

APPLICATION FILED MAY 26, 1917.

1,279,580.

Patented Sept. 24, 1918.

UNITED STATES PATENT OFFICE.

THEODORE PETERS, OF FERDINAND, INDIANA, ASSIGNOR TO THE PET-SON PUMP COMPANY, OF FERDINAND, INDIANA, A CORPORATION OF INDIANA.

AIR-PUMP FOR WATER-DISTRIBUTING SYSTEMS.

1,279,580.

Specification of Letters Patent. Patented Sept. 24, 1918.

Application filed May 26, 1917. Serial No. 171,311.

To all whom it may concern:

Be it known that I, THEODORE PETERS, a citizen of the United States, residing at Ferdinand, Indiana, have invented a certain 5 new and useful Improvement in Air-Pumps for Water-Distributing Systems, of which the following is a full, clear, and exact description, such as will enable others skilled in the art to which it appertains to make 10 and use the same.

This invention relates to water distributing systems of the type that comprise a water container or reservoir submerged in a well or other body of water, and an air 15 pump for creating pressure in said container, so as to cause the water in same to flow through a distributing pipe that leads to the place where water is to be consumed or used.

20. The main object of my present invention is to provide a water distributing system of the general type referred to that comprises a manually-operated pump which is so constructed that the pressure in the submerged water container will be relieved automatically when the operator releases the 25 actuating device of the air pump, thereby permitting the water container to automatically fill with water.

30. Another object is to provide a pump or water distributing system of the character referred to that can be installed easily and also adjusted easily, so as to vary the leverage of the actuating device.

35. And still another object is to provide an inexpensive air pump for the purpose described which is of such simple design that it is not apt to get out of order. Other objects and desirable features of my invention 40 will be hereinafter pointed out.

Figure 1 of the drawings is an elevational view, illustrating a water distributing system provided with an air pump constructed in accordance with my invention.

45. Fig. 2 is a top plan view of said air pump. Fig. 3 is a vertical sectional view, taken on the line 3-3 of Fig. 1.

Fig. 4 is a horizontal sectional view, taken on the line 4-4 of Fig. 1; and

50. Fig. 5 is a longitudinal sectional view, illustrating the air valve on the hand grip of the pump actuating device.

Referring to the drawings which illustrate the preferred form of my invention, 55 A designates a water container or reservoir

that is submerged in a well α or other body of water. B designates an air pump for creating pressure in said water container and C designates a conduit that leads from the water container A to the place where 60 water is to be used, said distributing pipe C being provided with a spigot C' or other controlling device. The water container A is provided at its lower end with an inwardly opening check valve 1 that controls 65 a port through which the water enters the container A, and the distributing pipe C is provided with a check valve 2 arranged in such a manner that it prevents the water in the distributing pipe from flowing backwardly into the container A. When the 70 pump is operated pressure is created in the container A, thereby causing the water to be forced out of said container through the distributing pipe C to the point where the 75 water is to be used.

In order that the container A will automatically fill with water, I have constructed the pump B in such a manner that when the operator releases the actuating device of said 80 pump pressure in the container A will be relieved, thereby permitting the check valve 1 to open, and thus cause the water from the source of supply to flow into the container A. In the form of my invention herein 85 shown the actuating device of the pump B consists of a hand lever D that is pivotally connected to the piston E of the pump, one end of said lever being pivotally connected to a rockable fulcrum member 3. The cylinder 4 of the pump is provided at its lower end with a laterally projecting pipe 5 that leads to a valve casing F, the inferior 90 of said valve casing being connected by means of a pipe 5^a with the interior of the water container A. Check valves 6 and 7 are arranged in the valve casing F in such a manner that when the piston E of the pump moves upwardly the valve 7 will seat 95 and the valve 6 will open and permit air to pass through a port 6^a in said valve casing, and thence through the pipe 5 into the cylinder 4 of the pump. On the downward stroke of the piston E the air which entered the cylinder of the pump on the upward stroke of the piston will be compressed and forced out of the cylinder 100 through the pipe 5 into the pipe 5^a that leads to the water container A, the valve 6 seating automatically and the valve 7 opening 105

110

automatically on the downward stroke of the piston E. The lever or actuating device D of the pump is provided with an air duct or passageway 8, shown in Fig. 4, which is 5 connected by means of a flexible conduit 9 with the valve casing F of the pump, said air duct 8 being provided with a discharge port 8^a that is controlled by a valve 10, shown in Fig. 5. When the valve 10 is open 10 the submerged water container is in direct communication with the atmosphere through the pipe 5^a, the flexible conduit 9 and the air duct or passageway 8 in the pump actuating device D, the conduit 9 being connected to 15 the valve casing F at a point between the discharge valve 7 and the air pipe 5^a that leads to the water container A, as shown more clearly in Fig. 3 of the drawings. It is immaterial, so far as my broad idea is concerned, 20 what type of air valve 10 is used for controlling the air discharge port 8^a, but I prefer to combine the valve 10 with a hand grip 11 on the actuating lever D in such a manner that when the operator releases said hand 25 grip, the valve 10 will open automatically, and thus permit the air to escape from the water container A. As shown in Figs. 1 and 5, the hand grip 11 is provided with a pivotally mounted portion 11^a, preferably arranged on the underside of same, and the 30 valve 10 is arranged on said pivotally mounted portion in such a manner that it will close the port 8^a when the hand of the operator grasps the portion 11^a of the hand grip and forces it upwardly. The valve 10 is normally held unseated by means of a 35 spring 12 that exerts pressure on the movable portion 11^a of the hand grip in a direction tending to force it away from the 40 stationary portion of said hand grip.

The cylinder of the pump and the rockable fulcrum member 3 are carried by a bracket G that can be easily connected to a wall or other supporting structure, and in 45 order that the pump may be adjusted so as to vary the leverage of the actuating device D, I have mounted the cylinder of the pump on the supporting bracket G in such a manner that said cylinder can be moved toward or 50 away from the rockable fulcrum member 3. As shown in Fig. 3 of the drawings, the cylinder of the pump is provided at its lower end with a non-circular-shaped projection 13 that passes downwardly through an elongated slot 14 on the supporting bracket G, said projection having a threaded portion 13^a on which a nut 15 is mounted so as to 55 securely clamp the cylinder to the supporting bracket. The piston rod 16 of the pump 60 is pivotally connected at its upper end to a sleeve 17 that is adjustably mounted on the pump actuating lever D, said sleeve being held in operative position on said lever by frictional engagement with same, or in any 65 other desired manner. By loosening the

clamping nut 15 and moving the cylinder of the pump toward or away from the fulcrum member 3, and also moving the sleeve 17 longitudinally of the lever D, the leverage of the actuating device D can be easily varied, thereby enabling the pump to be adjusted in such a manner that it can be easily operated by a child. 70

The particular details of construction of the pump are of course immaterial so far as 75 my broad idea is concerned, but in order that the pump can be manufactured and sold at a low cost, and in order that it will successfully withstand rough, continuous usage, I prefer to form the actuating device D of 80 the pump from a piece of ordinary metal pipe whose end is secured to a casting 18 provided with integral ears 19 that embrace the fulcrum member 3 and which are secured to said member by means of a pivot 20. The fulcrum member 3 is also preferably formed from a piece of pipe whose lower end is connected to a casting 21 that is pivotally connected by a pin 22 to integral lugs or ears 23 on the bracket G. The hand grip 11 also 85 preferably consists of a hollow casting into which one end of the actuating device D is threaded. The valve casing F can be formed conveniently from a casting of simple 90 design screwed onto the end of the pipe 5 that projects laterally from the cylinder of 95 the pump and provided with an integral nipple 24 over which the lower end of the flexible conduit 9 can be slipped, the upper end of said flexible conduit being slipped over an integral nipple 25 on the casting 18 on the end of the actuating device D. 100

Having thus described my invention, what I claim, and desire to secure by Letters Patent, is: 105

1. An air pump for the purpose described provided with an actuating device, an air supply pipe through which air is forced when the piston of said pump moves in one direction, an air discharge pipe that communicates with said air supply pipe, and means carried by said actuating device for opening and closing said air discharge pipe. 110

2. An air pump provided with an operating lever, and means carried by said lever for automatically relieving the pressure produced by the movement of the piston of said pump whenever the lever is released by the operator. 115

3. An air pump provided with an operating lever, an air duct in said lever that communicates with a means to which the pump supplies air, and a valve on said lever for controlling said air duct. 120

4. An air pump provided with an operating lever, a hand grip on said lever, an air duct in said lever that communicates with a means to which the pump supplies air, and a valve on said hand grip for controlling said air duct. 125 130

5. An air pump provided with a pipe through which air under pressure flows from said pump, an operating lever for said pump provided with a hand grip, an air duct in said lever, a flexible conduit that connects said air duct with a pipe through which air flows from the pump, and a valve on said hand grip for controlling said air duct. 40
6. An air pump, comprising a cylinder 10 provided with a piston, an operating lever for actuating said piston, said lever being equipped with an air duct, a valve on said lever for controlling said air duct, means which tends to normally hold said valve 45 open, and a connection between said air duct and a means to which the pump supplies air. 15
7. An air pump, comprising a cylinder provided with a piston, a hand lever for actuating said piston, an air duct in said 20 lever, a hand grip on said lever provided with a spring actuated portion that is equipped with a valve for governing said air duct, a valve casing connected with one end of the cylinder of the pump and provided with an inlet valve and an outlet valve, a supply pipe leading from said valve casing to the member to which the pump supplies air, and an air conduit communicating with the air duct and connected to said valve casing at a point between said supply pipe and 25 said outlet valve. 30
8. An air pump, comprising a cylinder, a supporting bracket that carries said cylinder, a rockable fulcrum member on said bracket, an actuating lever for said pump pivotally connected to said fulcrum member, means for permitting said cylinder to be adjusted 35
- toward and away from said fulcrum member so as to vary the leverage of said operating lever, an air duct in said lever that normally establishes communication between the atmosphere and the means to which the pump supplies air, and means for closing said duct when said lever is being actuated. 45
9. An air pump, comprising a cylinder 50 provided with a piston, an operating lever for said pump formed from a pipe or piece of tubing, a hollow hand grip on said pipe provided with an air discharge port and a movable portion equipped with a valve that controls said port, and a flexible conduit that establishes communication between said pipe and the means to which the pump supplies air. 55
10. An air pump, comprising a cylinder 60 provided with a piston, a supporting bracket for said cylinder provided with an elongated slot, a guiding device on the bottom of said cylinder that projects into said slot, means on said guiding device for clamping the cylinder to said bracket, a rockable fulcrum member pivotally connected to integral lugs on said bracket, an operating lever for said pump formed from a piece of pipe or tubing, a casting on one end of said pipe pivotally connected to said fulcrum member, a sleeve slidingly mounted on said pipe and pivotally connected to the rod on said piston, a hand grip on said lever provided with an air discharge port, and a pivotally mounted, 65 spring-actuated portion on said hand grip provided with a valve for controlling said port. 70

THEODORE PETERS.
